UNITED STATES PATENT OFFICE.

EMILE MASLIN, OF L'ESTAQUE, FRANCE.

INEXPLOSIVE STEAM-BOILER.

1,059,481.

Specification of Letters Patent. Patented Apr. 22, 1913.

Application filed January 28, 1911. Serial No. 605,252.

To all whom it may concern:

Be it known that I, EMILE MASLIN, a citizen of the French Republic, residing at L'Estaque, Banlieue de Marseille, Bouches-du-Rhône, in the Republic of France, have invented certain new and useful Improvements in Inexplosive Steam-Boilers, of which the following is a specification.

This invention relates to an improved in-explosive-steam boiler in which the boiler is insulated and separated from the furnace, the heat being transmitted from the furnace to the boiler by means of a fluid circulating in endless tubes. The elements consisting of 10 endless tubes are located with their lower ends in the furnace and flue and with their upper ends in the boiler so that the liquid contained in said elements is vaporized in the lower end of the same to condense in the 15 upper end and to return again to the lower end.

In the accompanying drawings the invention is shown.

Figure 1 is a cross section of Fig. 3 along 20 the line U—V, Fig. 2 is a cross section along the line Y—Z of Fig. 3, and Fig. 3 represents a longitudinal section taken along the axis of the boiler and the flue.

The gases of combustion and the flames 25 are conducted from the grate *a* of the furnace through the flue *b* (Fig. 3) which they traverse from end to end to escape through the chimney. The walls of the flue and the walls of the furnace are of sheet metal and 30 internally lined with refractory material so as to be effectively protected against the destructive action of the fire and to reduce the loss of heat by radiation.

The simplest type of thermo-siphon consists of an endless tube *c* (Fig. 3) which is 35 curved so as to form a lower horizontal part situated in the flue, and an upper vertical part penetrating into the boiler. Where the tubes traverse the wall or shell of the boiler 40 stuffing-boxes are arranged. Each of the thermo-siphons communicates permanently by means of a capillary tube *f* (Fig. 2) with a small air reservoir *g* which is closed by a lid. This reservoir is destined to permit the 45 free expansion of the liquid which fills the siphon and further to facilitate the refilling of the same. A capillary tube *h* upon the upper end of the siphon permits the escape 50 of the air during the filling of the siphon. 55 The reservoir *g* and the capillary tube *h* must be closed hermetically after the siphon

has been filled which is very important for the proper working of the apparatus. The tubes which form the thermo-siphons can be of iron, copper or aluminium according to 60 the nature of the liquid which circulates in said siphons. If the thermo-siphon has been once mounted and filled, it does not require any further attention; as soon as the hot gases pass through the flue, the liquid in the 65 siphon begins to circulate and to transmit the heat from the flue to the boiler absolutely regularly and automatically.

It is evident that the heating surfaces of the thermo-siphons at the rear end of the 70 flue have to be much larger than those of the thermo-siphons which are nearer to the inlet of the flue so as to compensate for the gradually decreasing heat of the gases from combustion. In order to increase the heating 75 surfaces, the part *m* of the tube *i* (Fig. 3) could be wound in a spiral, or as shown in Fig. 3 the tube *j* or *k* is divided into two, four, eight, sixteen, etc., arms. As the liquid which circulates in the siphon tubes 80 does not form any deposit the inner diameter of said secondary branches of the tubes can be very small so that a very large heating surface is obtained without increasing the 85 weight of the device or the space required.

The surface of the thermo-siphons destined to communicate the heat to the generator can be greatly increased by adding external ribs of metal to the parts of the tubes which penetrate into the boiler, said ribs 90 *l* (Fig. 3) being soldered upon said tubes. The radiating surface of the tubes could also be increased by giving a spiral shape to said tubes (see *m* Fig. 3) or by dividing them into arms.

The heating device *n* (Fig. 3) is composed of a small nest of tubes made of forged iron, having an inner diameter of from eight to twelve millimeters. These tubes, the same as those of the thermo-siphons, can be either straight or spiral-shaped, *m* (Fig. 3). They all communicate at their lower end with the feed tube *o* (Fig. 3) and at the upper end with a small reservoir *p* (Fig. 3) which serves to separate the steam 105 and upon which is mounted the steam tube *q* (Figs. 1 and 3). This steam tube traverses the wall of the steam-generator in a stuffing-box and it terminates at the upper end of the condenser *r* (Fig. 1). This condenser itself is composed of tubes of very 110 small diameter which are made of iron or

copper, straight or spiral shaped. The vapor or steam of the auxiliary fluid transmits the heat from the furnace to the water of the main generator, the condensed liquid flowing back to the evaporating apparatus through the feed tube *o* (Fig. 3). The liquid filling the tubes thus continuously circulates in vaporizing in the flue, condensing in the generator, returning in liquid state to the flue, vaporizing again and so forth. As is the case with the thermosiphons the transmission of the heat is effected automatically and requires no attention.

15 I claim:—

1. An improved inexplosive steam boiler as described and shown in the drawings comprising in combination the furnace with heating flues, the boiler insulated and separated from said furnace, elements each formed of an endless tube located with the lower part in said furnace and with the upper part in said boiler; a liquid filling said tubes for transmitting the heat from

the furnace to the boiler, said liquid vaporizing in the lower part of the tube and condensing in the upper part of the same. 25

2. An improved inexplosive steam boiler comprising in combination the furnace with heating flues, the boiler insulated and separated from said furnace, elements each formed of an endless tube connecting said furnace with said boiler, the lower part of said elements projecting in the furnace and being formed so as to increase the heating surface, the upper part of said elements located in the boiler and formed so as to increase the radiating surface, a liquid filling said tubes for transmitting the heat from the furnace to the boiler, substantially 30 35 40 as described and shown and for the purpose set forth.

In witness whereof I have hereunto set my hand in the presence of two witnesses.

EMILE MASLIN.
